HERBERT C. EVERED AND ALBERT R. EVERED, OF ROCHESTER, NEW YORK.

STOVEPIPE-DAMPER.

1,288,540.

Specification of Letters Patent. Patented Dec. 24, 1918.

Application filed August 24, 1916. Serial No. 116,711.

To all whom it may concern:

Be it known that we, HERBERT C. EVERED and ALBERT R. EVERED, citizens of the United States, residing at Rochester, in the county of Monroe and State of New York, have invented certain new and useful Improvements in Stovepipe-Dampers, of which the following is a specification.

This invention relates to pipe dampers and is adapted for use in connection with stoves and furnaces.

An object of the invention is to provide improvements in means for increasing the heating efficiency of stoves and furnaces, and for obtaining the greatest possible amount of heat from the fuel used. A further object of the invention is to provide means for use in preventing back drafts in the flue or smoke pipe gaining access to the stove or furnace, and for controlling heat passing into the flue. A still further object of the invention is to provide means within the stove or furnace pipe for controlling the escape of gases from the fire pot, whereby the latter are confined within the stove or furnace until spent or consumed. A still further object is to provide means of this character which operates to thoroughly and completely consume all of the fuel fed into the fire pot. A still further and particular object of the invention is to provide means within the draft pipe of the stove or furnace which may be operated to check the draft in the chimney without the necessity of closing the front dampers of the stove or furnace, whereby the fire within the stove is at all times sufficiently supplied with oxygen to perfect combustion.

With these objects in view, together with others which will appear as the description proceeds, the invention resides in the novel formation, combination, and arrangement of parts, all as will be described more fully hereinafter, illustrated in the accompanying drawings, and particularly pointed out in the claims.

The invention will be best understood with reference to the accompanying drawings, wherein:—

50 Figure 1 is a longitudinal sectional view taken through a portion of a stove pipe and illustrating the application of an intensifying device constructed in accordance with our invention;

55 Fig. 2 is an elevational view of the device; and

Fig. 3 is a transverse sectional view taken through the pipe substantially upon line 3—3 of Fig. 1.

Referring now more particularly to the drawings, 5 indicates a conventional form of smoke pipe for establishing communication between the stove or furnace and the chimney or flue. The invention consists generally in the arrangement of a valve within the smoke pipe at any suitable point, capable of being actuated so as not to retard or in any way affect the draft through the furnace smoke pipe and flue, and which when required may be operated to check or control the draft so as to prevent loss of the heat units before being entirely utilized.

In carrying the invention into effect, a frame member 6 is secured around an opening 6' in the smoke pipe 5 by means of bolts 7 or rivets. In the present instance, this frame is substantially rectangular in shape, and has a similarly shaped inner opening, from the edges of which right angularly disposed flanges 8 extend. The flanges project through the opening 6' a relatively short distance into the interior of the smoke pipe 5, and one of the flanges is equipped at one end with laterally alined ears 9. These ears are provided with openings in registration with each other, within which the ends of a pin 10 are rotatably mounted, the said pin being fastened to one end of a plate 11 constituting a valve for swinging toward and away from the opening defined by the flanges 8. The plate or valve 11 is adapted when swung into the position indicated by full lines in Fig. 1, to entirely close the inner opening in the frame 6, and when swung to open position, or that indicated by dotted lines in Fig. 1, uncovers the opening defined by the inner edges of the flanges 8, and substantially closes the passage in the smoke pipe. The lateral edges of the plate 11 are cut away as shown, whereby the plate edges 100 are spaced from the interior walls of the smoke pipe when the valve is swung to open position. (See Fig. 3). The arrow in Fig. 1 of the drawings, indicates the direction of draft in the smoke pipe, and it is apparent that when the valve 11 is swung downwardly, the draft will be materially checked, certain parts of the heated air, however, passing around the lateral edges of the plate 11 and into the chimney. This arrangement 110 confines the bulk of the products of combustion within the fire pot of the stove or fur-

nace, whereby the live gases which ordinarily pass into the chimney are saved and confined for complete combustion. The force of the products of combustion in es-
5 capping around the lateral edges of the valve
11 prevents cold air gaining access to the fire pot of the furnace. When the valve is
in the position indicated in Fig. 3, the front
10 drafts of the stove or furnace may remain
open, whereby sufficient oxygen may be ad-
mitted to the fire box to promote thorough
combustion, without allowing the stove or
furnace a draft sufficient to rapidly burn out
15 the fire. The valve may be moved to any
number of positions, whereby the draft in
the fire pot may be minutely governed.

A lever 12 is secured at one end as at
13 to the plate 11, and extends in an out-
ward and rearward direction therefrom,
20 and has secured to its outer or free end,
one end of a cable, or cord 14. This cord
passes forwardly across the opening in the
frame 8 and extends over a pulley 15 se-
cured to the bracket 16. The flexible mem-
25 ber 14 may then be passed to any suitable
place beyond the stove or furnace in po-
sition for convenient manipulation. A
standard 17 is secured as at 18 to the frame
6 adjacent the rear end thereof, and has
30 secured thereto, one end of a contractile
spring 18', the opposite end of the said
spring being secured to a toe 19 constitut-
ing the inner end of the lever 12. It will
thus be seen that the spring 18' normally
35 exerts upward pressure upon the valve plate
11, whereby the latter is maintained in
closed position. Upon pull being exerted
to the flexible member 14, the lever 12 in
its upward movement rocks the plate 11
40 upon its pivot 10 to open position. The
cord 14 may be fastened so as to hold the
valve in any of its positions of adjustment.

From the foregoing, it is seen that we
have provided an extremely simple and yet
45 thoroughly efficient means for attaining the
objects set forth, and while the above is a
description of the preferred embodiment of
the invention, it is obvious that, if desired,
certain changes in the minor details of con-
50 struction and arrangement of parts may be

resorted to, without departing from the
spirit of the invention, or exceeding the
scope of the claims.

What is claimed is:—

1. In a device of the class described, the 55
combination with a stove pipe having an
opening therein, of a frame secured to said
pipe around said opening, flanges on said
frame extending into said pipe, a valve plate
50 pivoted to one end of one of said flanges
and being adapted to close the inner opening
of the frame, a lever secured at one end
to the outer face of said plate and adjacent
the hinges thereof, the said lever extending
55 outwardly at a right angle to said plate and
being bent rearwardly adjacent its outer
end beyond said frame in a direction par-
allel with said pipe, a pulley mounted on
said frame at one end thereof and in sub-
stantially the same horizontal plane with
60 the free end of said lever, a spring for nor-
mally holding said plate in closed position,
and a cord passing over said pulley and be-
ing connected to the free end of said lever,
substantially as described. 75

2. As an article of manufacture, a rec-
tangular frame having right angularly dis-
posed flanges at its inner edges, a plate
hinged to the end of one of said flanges and
being adapted to rest at its edges against
the remaining flanges, a standard secured to
70 said frame and projecting over the open-
ing formed thereby, a contractile spring
secured at one end to said plate and at its
opposite end to said standard, an arm se-
cured at its inner end to said plate and
80 projecting outwardly at a right angle to
said plate, the end of said arm being bent
rearwardly at a right angle, a pulley on
said frame opposite said standard, and a
90 cord connected to the free end of said arm
and passing over said pulley, substantially
as described. 85

In testimony whereof we affix our signa-
tures in presence of two witnesses.
